ARCH AND ANKLE SUPPORT

John Joseph Cartledge, Guelph, Ontario, Canada,
assignor of one-half to H. Stewart Jones, Lon-
don, Ontario, Canada

Application March 27, 1934, Serial No. 717,655
In Canada February 23, 1934

1 Claim. (Cl. 128—166.5)

This invention relates to arch and ankle supports, and more specifically to combined arch and ankle supports of the elastic type.

The main object of the invention resides in the provision of an arch and ankle support so combined in one unit that the arch and instep of the foot are fully surrounded as well as the arch being supported in the usual way.

Another object is to provide a combined arch and ankle support which shall have, as desired, lateral stretch or elasticity at the meeting point of the two parts thereof.

Another object is to provide a combined arch and ankle support the elasticity of which extends from the ankle portion to the arch portion both longitudinally and laterally of the foot resulting in a perfect fit of the support, ensuring complete comfort at all times.

Other objects as well as many advantages of the supports forming the subject matter of this invention will become apparent in the following description, supplemented by the drawing which illustrates in perspective a combined support, in accordance with this invention as applied to the foot.

The support includes a vertically disposed ankle encompassing portion or section 5 formed of a strip of elastic fabric 5' standing on one of its lengthwise edges and overlapping upon itself to provide a vertically disposed band. The ends of strip 5' are anchored together, as at 6 to maintain it in band-like form.

The support also includes a horizontally disposed arch encompassing portion or section 7 formed of a strip of elastic fabric 7' corresponding in width to and of greater length than that

of the strip 5'. The ends of strip 7' are cut on a bias. The strip 7' stands upon one of its side faces, is overlapped upon itself to provide a horizontally disposed band and to position its bias end edges flush with each other. The flush edges of the strip 7' are secured against the front of the inner edge of section 5 by a row of stitching 9 whereby strip 7' is maintained in band-like form and section 7 is arranged below and extends outwardly at right angles to the front of section 5.

It will be noted, in the figure, that both ends meet and that the angle of the cut tends to direct the strip to each side of the foot.

The arch and ankle support are joined by means, which may be for example, elastic stitching, to provide lateral stretch or elasticity at the meeting of the two parts thereof.

In use, the supports are fitted to the foot in the usual manner by first inserting the foot through the ankle portion and raising same over the heel at the same time stretching the arch portion and sliding same over the foot until it assumes a comfortable bearing around the arch and instep.

What I claim is:

In a support, an ankle encircling band of stretchable material, an arch support consisting of a band of stretchable material completely encircling the arch, the ends of said arch support overlapping each other and being joined and secured at the lower front part of said ankle encircling band, and longitudinally elastic means joining said ankle band and said arch support as aforesaid, to permit longitudinal elasticity of the joint itself.

JOHN JOSEPH CARTLEDGE.
